UNITED STATES PATENT OFFICE.

NETTIE H. CUDDEBACK, OF LOS ANGELES, CALIFORNIA.

SUNBONNET

932,968.

Specification of Letters Patent. Patented Aug. 31, 1909.

Application filed August 3, 1908. Serial No. 446,666.

To all whom it may concern:

Be it known that I, NETTIE H. CUDDEBACK, a citizen of the United States, residing at Los Angeles, in the county of Los Angeles and State of California, have invented new and useful Improvements in Sunbonnets, of which the following is a specification.

The object of this invention is to provide a sunbonnet with a wide flare in front, there being a combination of a number of parts to effect this end. The front piece, or vizor, is cut in a peculiar configuration and the crown piece is so gathered and held as to force the front piece to assume a widely flared position. The crown piece is gathered around a resilient member which adapts the bonnet to different sized heads and the resilient member is made removable so that the body parts of the bonnet may be washed.

20 In the accompanying drawings, forming a part of this specification:—Figure 1,— is a view showing my improved sunbonnet in use. Fig. 2,— is a plan view showing the inside of the bonnet flattened out and with the 25 resilient member removed. Fig. 3,— is a view of the resilient member. Fig. 4,— is an enlarged detail view of one of the corners of the front piece, or vizor.

20 In the drawings 5 designates the front piece or vizor which is preferably made of rice straw matting as that material affords protection from the heat of the sun and is extremely light and flexible. This vizor is crescent shape and is provided with a binding 6 around its entire edge, the binding widening as at 7 at the corners or ends of the crescent shaped vizor where bonnet strings 8 are attached, this widening portion affording reinforcement to the straw matting to prevent its being torn by any excessive pull upon strings 8. Crown piece 9 is cut in an oval or elliptical shape and is sewn to the concave edge of vizor 5 along a line of stitching 10, the stitching passing 40 through the crown piece back of its edge the edge being ruffled as at 11. Cape piece 12 is cut in a somewhat rectangular form with rounded corners and is sewn to the crown piece along two lines of stitching 13 so that 45 a casing 14 is left between the crown and cape pieces between these two lines of stitching. A strip 15 of rubber fabric is inserted in casing 14 and is provided with eyelets 16 on its ends adapted to engage with snap 50 hooks 17 secured to the ends or corners of

crecent shaped vizor 5. The end pieces of cape piece 12 are secured to the corner of the vizor as shown most clearly in Fig. 4, strings 8 being also secured near the corners. A ruffle 18 is placed around the convex or front 60 and bottom edges of the vizor to finish the bonnet.

When resilient strip 15 is in place the two ends of the crescent shaped vizor are drawn closely together and the whole bonnet assumes the position shown in Fig. 1, the bottom part of the crown piece and the upper part of the cape piece being held closely to the back of the wearer's head and the front part of the vizor flared outwardly. The 65 crescent shape of the vizor brings its ends behind the wearer's ears as illustrated in dotted lines in Fig. 1 and strings 8 also attached to the vizor behind the ears. On account of this position any tightening of 70 the strings immediately draws the rear and bottom portions of the vizor together and against the wearer's head so that the upper and side portions are greatly flared. The 75 portions of the vizor directly opposite the ears are also flared out on account of the above provision and the ears are thereby left free from any covering which might hinder or impair the hearing. Further it 80 will be noted that the wide flare of the front of the bonnet affords access for the atmosphere and does not tightly inclose the wearer's head, thus providing a cool head gear at all times.

From the foregoing description it will be 90 seen that my invention consists in the described combination and arrangement of parts to provide a bonnet which fits closely in the rear and flares widely in front. This provision depends essentially upon the crescent shaped front piece or vizor and the resilient strip 15 which holds the back of the bonnet close to the wearer's head. The 95 effect is increased further by the attachment of the bonnet strings to a point on the vizor 100 at the place where they will pull the rear-most portions of the vizor inwardly and against the wearer's head. All these combinations have been provided in an easily 105 constructed and handy manner. The bonnet may be rolled up and thus placed in a small compass for transportation and it may be also laundered very easily. The rice straw matting used in the construction of the bonnet is very flexible in a line transverse to the 110

direction of its straws and it therefore lends itself very readily to the operations of rolling or laundering.

Having described my invention what I claim as new and desire to secure by Letters Patent is:—

1. A bonnet, comprising a crescent shaped vizor, and a removable resilient connecting member between the ends of the crescent.
- 10 2. A bonnet, comprising a crescent shaped vizor, a removable resilient connecting member between the ends of the crescent, and bonnet securing strings attached to the crescent near the ends thereof.

3. A bonnet, comprising a crescent shaped vizor, a crown piece secured thereto, a removable resilient connecting member between the ends of the corner piece, the crown piece being gathered along the resilient member, and bonnet securing strings attached to the crescent near the ends thereof.

In witness that I claim the foregoing I have hereunto subscribed my name this 28th day of July, 1908.

NETTIE H. CUDDEBACK.
